BAKERY TRAY OR THE LIKE

Hugh B. Fraser and Gale S. Roush, Bartlesville, Okla.,
assignors to Phillips Petroleum Company

Filed May 26, 1972, Ser. No. 57,489

Term of patent 14 years

FIG. 2

FIG. 3

FIG. 4

FIG. 5

FIG. 6

FIG. 7

FIG. 1 is a top plan view of a bakery tray or the like showing our new design;

FIG. 2 is a bottom plan view;

FIG. 3 is an end elevational view, the opposite end being substantially the same in appearance as the end shown;

FIG. 4 is a side elevational view, the opposite side being substantially the same in appearance as the side shown; and

FIG. 5 is an enlarged cross-sectional view thereof taken on the line 5—5 of FIG. 1,

FIG. 6 is a top plan view showing a modified form of our new design;

FIG. 7 is a bottom plan view;

FIG. 8 is an end elevational view, the opposite end being substantially the same in appearance as the end shown; and

FIG. 9 is a side elevational view thereof, the opposite side being substantially the same in appearance as the side shown.

We claim:

The ornamental design for a bakery tray or the like, as shown and described.
